US00D645045S

(12) **United States Design Patent**
Cacioppo et al.

(10) **Patent No.:** **US D645,045 S**
(45) **Date of Patent:** **** Sep. 13, 2011**

(54) **REMOTE**

(75) Inventors: **Christopher M. Cacioppo**, Somerville, MA (US); **Manuel Perez**, Somerville, MA (US); **Hector Padilla**, Chelsea, MA (US); **Timothy Higgins**, Allston, MA (US); **Louis Frank Genatossio**, Shrewsbury, MA (US); **Rick Burnham**, Gloucester, MA (US); **Dan DeOreo**, Manchester, MA (US)

(73) Assignee: **Sanford, L.P.**, Oak Brook, IL (US)

(**) Term: **14 Years**

(21) Appl. No.: **29/383,993**

(22) Filed: **Jan. 25, 2011**

Related U.S. Application Data

(62) Division of application No. 29/353,000, filed on Dec. 30, 2009, now Pat. No. Des. 633,910.

(51) **LOC (9) Cl.** **14-02**

(52) **U.S. Cl.** **D14/388; D14/218**

(57) **CLAIM**

The ornamental design for a remote, as shown and described.

DESCRIPTION

FIG. 1 is a perspective view showing my new design for a remote;

FIG. 2 is a front view of the remote of FIG. 1;

FIG. 3 is a back view of the remote of FIG. 1;

FIG. 4 is a left side view of the remote of FIG. 1;

FIG. 5 is a right side view of the remote of FIG. 1;

FIG. 6 is a top plan view of the remote of FIG. 1; and,

FIG. 7 is a bottom plan view of the remote of FIG. 1.

The broken lines in the drawings illustrate the boundaries of the claimed design. The broken line boundaries and the areas therewithin form no part of the claimed design.

1 Claim, 5 Drawing Sheets
